HANS S. MATTISON, OF LA CROSSE, WISCONSIN, ASSIGNOR, BY DIRECT AND MESNE ASSIGNMENTS, TO NEW ERA PRODUCTS COMPANY, OF MINNEAPOLIS, MINNESOTA, A MASSACHUSETTS TRUST ASSOCIATION.

HEATING SYSTEM FOR INTAKE MANIFOLDS AND CIRCUIT FOR SAME.

Application filed October 29, 1924. Serial No. 746,631.

One object of my invention is to provide a heating device to be used in connection with an intake manifold for heating gases passing through the manifold and for straining the gases through heated wires.

Another object of my invention is to provide improved means for positioning a heating coil on the interior of an intake manifold.

10 Another object is to provide a coil and a circuit such that the coil will deliver the greater amount of heat when the motor to which it is attached is being started and a lesser but sufficient amount of heat for running conditions when the motor is running.

With these and incidental objects in view, the invention consists of certain novel features of construction and combination of parts, the essential elements of which are 20 hereinafter described with reference to the drawing which accompanies and forms a part of this specification.

25 In the drawing, Figure 1 is a plan view of my improved heater and showing circuit arrangements therefor.

As shown in the drawing the heater is comprised of a gasket 1, adapted to be placed between a carburetor and an intake manifold of a gasoline engine, apertures 2 30 and 3 being provided for taking the ordinary fastening bolts.

This gasket may be made of metal, but I prefer a substance on the order of bakelite or some insulating material, and the large 35 aperture 4, which is in line with the intake manifold has a circumferential recess there-around, as shown at 5.

When a motor is first being started a great deal more heat should be applied to the gases 40 than is necessary when the motor is running and for that reason I have provided a circuit that will insure such operation of the heating coil.

As shown in the drawing, the battery B is 45 connected by wires 10 and 11 to the contact 12 adapted to contact with a contact plate 12' on the free end of a switch bar S, pivoted at S', when the switch bar S is turned up manually against contact 12 by any suitable means (not shown). A wire 13 leads 50 from the pivoted end S' of bar S to a contact terminal T fixed in the usual manner to the gasket 1 and a conductor 14 connects this

terminal T to the center of the coil 9, the upper half of which is designated by the 55 reference numeral 15, and has its end connected to a terminal T² fixed to gasket 1.

The terminal T² is connected by wire 16, to the pivot end S² of a switch bar S³ connected by a link L to the bar S, the bars S 60 and S³ thus linked, constituting a double pole switch of ordinary construction. When the engine is at rest, the bar S³ rests on the contact 17' and link L holds bar S with contact plate 12' separated from contact 12. 65

The terminal T³ fixed on plate 1 and connected to the lower half of coil 9 is connected by wire 18 to the contact point 17. The contacts 17 and 17' are fixed relative to each other and the bar S³ as previously described 70 rests normally on contact 17'. It is only when the double pole switch is raised manually or otherwise, that contact is made between plate 12' and contact 12 and bar S³ contacts with point 17. The wire 18 is also 75 connected by wire 19 to the ground 20, and a wire 22 tapped to wire 19 serves as a return line to battery B.

A wire 23 connects contact point 17' to one terminal of the ignition switch 25 and a 80 wire 24 connects the other terminal of this switch 25 through ammeter A to the battery wire 10.

In operation, as soon as the motor starter is operated, the two pole switch is moved upward manually so that bar S³ leaves contact 17' and contacts with contact point 17, and the plate 12' contacts with contact point 12. In this condition the circuit is through battery B, wires 10 and 11, contact 12, plate 12', 85 bar S, wire 13, terminal T, wire 14 upper half 15 of coil 9, terminal T², wire 16, contact 17, and wires 18 and 19 to ground 20 or return wire 22 to battery B, wire 22 being the ground wire for the battery. The current also flows from wire 14 through lower half 21 of coil 9 to terminal S³ and wires 18 and 19 to ground 20. During the operation of the starter motor, or as long as the double pole switch is closed, the battery current under full voltage passes in parallel through the two halves of the coil and hence gives the maximum heating effect of the coil, which is, of course, highly desirable at the starting of the motor. 95

100 As soon as the engine is running inde-

pendently of the starter motor, the two pole switch may be released, bar S^3 then drops into contact with contact 17' and away from contact 17 and bar S leaves contact 12. The circuit then is: through battery B, wires 10 and 24, ammeter A, switch 25, wire 23 contact 17', bar S^3 , wire 16, terminal T^2 , the two halves of coils 15 and 21 in series, terminal T^3 , and wires 18 and 19 to ground 20.

10 The switch S^3 is obviously between the contacts 17 and 17'; and the link L connects the switches S and S^3 to form a double pole switch adapted to make contact with contacts 12 and 17 only when the compound 15 switch is operated manually, the combined link and switches thus forming a double-pole double throw switch.

The connections to the starting motor and switches, ignition circuits, and generator are 20 of the ordinary type but do not alter nor are they altered by the circuit arrangements for this heater.

While I have described my invention and illustrated it in one particular design, I do not wish it understood that I limit myself 25 to this construction, as it is evident that the application of the invention may be varied in many ways within the scope of the following claim:

Claim:

The combination with a sectional heating coil positioned in the line between the carburetor and intake manifold of an internal combustion engine, an electric circuit including said coil and a tap connected to the divisional point of said coil, and a double-throw double-pole switch in said circuit adapted when in one contact position to cause energy to flow through the two sections of said coil in parallel, and when in 40 the other contact position to cause current to flow through said sections in series.

HANS S. MATTISON.
